UNITED STATES PATENT OFFICE.

WILLIAM G. ALLAN, OF TORONTO, ONTARIO, CANADA, ASSIGNOR TO THE TORONTO POWER COMPANY, LIMITED, OF TORONTO, CANADA, A CORPORATION OF ONTARIO, CANADA

ELECTROLYTIC CELL STRUCTURE.

Application filed September 2, 1920. Serial No. 407,639.

To all whom it may concern:

Be it known that I, WILLIAM G. ALLAN, a subject of the King of Great Britain, residing at Toronto, county of York, Province 5 of Ontario, Canada, have invented certain new and useful Improvements in Electrolytic Cell Structures; and I do hereby declare the following to be a full, clear, and exact description of the invention, such as 10 will enable others skilled in the art to which it appertains to make and use the same.

This invention relates to electrolytic cell structures; and it relates more particularly, though not exclusively, to electrolytic apparatus 15 for production of hydrogen and oxygen from water.

In certain types of electrolytic apparatus, the casing containing the electrodes and dia- 20 phragm or diaphragms is composed of flanged members suitably assembled and held together to provide a container within which the electrolysis is carried on. The present invention is directed more particu- 25 larly to means for holding the aforesaid flanged members structurally assembled in such manner that the component parts of the cell or generator structure can be readily put together or taken apart with minimum inconvenience and expenditure of 30 labor, while at the same time the parts of the assembled structure are held together effectively and are not subject to accidental displacement or other objections.

In accordance with the present invention, 35 the cell frame or casing members are provided with flanges which cooperate in mating pairs, the flanges of each such pair being secured together by detachable clamp- 40 ing means extending around the outer edges of the cooperating flanges. Such clamping means may assume various different forms, but in general may comprise a pair of clamping jaws or arms adapted to engage 45 non-adjacent faces of cooperating flanges to press said flanges firmly toward each other.

The invention also comprises the provi- 50 sion of a novel combination of an electrode supporting plate with one or more flanged frame members to form a distinct unit capable of being assembled with other units of similar character in the construction of a complete generator unit.

These and other novel features and ad- 55 vantages of the invention will be more ap-

parent from the description hereinafter, 55 taken in conjunction with the accompanying drawings, and will then be more particularly pointed out.

In the accompanying drawings,

Figure 1 is a sectional view of apparatus 60 embodying the principles of the invention;

Figure 2 is a view in elevation at right angles to Fig. 1, showing the staggered ar- 65 rangement of the flange-clamping devices;

Figure 3 is a sectional view, similar to 70 Figure 1 but illustrating another form in which the invention may be embodied; and

Figure 4 is a view in elevation at right angles to Figure 3.

Referring to the drawings, 10 represents 70 an electrode supporting or backing plate carrying active electrodes 11 on opposite sides thereof, which are mounted upon said plate and secured in spaced relation thereto by means of stud devices 12 anchored to said plate and welded or otherwise suitably connected to the margins of the said electrodes. In the construction shown in Fig. 1, the bi- 75 polar electrode structure thus constituted is clamped between the cooperating inwardly 80 extending flanges 13 of annular cell frame or casing members each having a body por- 85 tion 14 and an outwardly extending flange 15. The outwardly extending flanges 15 co- 90 operate in pairs to support previous dia- 95 phragms. In this instance the diaphragms have rubberized margins 17, and a strip of thin sheet packing and insulating mate- 100 rial 18 is folded around the edge of the diaphragm and prevents direct contact thereof with the adjacent faces of the flanges 15. A spacing gasket 19 of soft rub- 105 ber or the like, fills the remaining space be- 110 tween the flanges 15 and most desirably pro- 115 jects somewhat beyond their outer edges, as shown. Said flanges 15 are held tightly 120 compressed against said gasket and the cov- 125 ered edge of the diaphragm by means of a 130 plurality of clamping devices 20 having ta- 135 pered jaws 21 pressing against the non-adjacent 140 faces of said flanges but separated therefrom in this instance by a sheet of 145 packing and insulating material 22 folded 150 around the flange edges. The U-shaped 155 clamping members 20 are made of metal 160 that has a certain degree of resiliency, such 165 as tempered steel for example, and in the 170 best embodiment of the invention, the edges

of the space between the arms 21 are almost but not quite parallel, the space narrowing slightly toward the rounded ends of the arms. These clamps are adapted to be driven on over the upper edges of the cooperating flanges 15, the arms 21 being slightly sprung apart in this operation and therefore firmly clamping the said flanges between them. The clamps may be applied at intervals in the required number around the periphery of the cooperating flange pairs, and the clamp devices of successive sets may be staggered as indicated in Fig. 2, this staggered arrangement being essential where two pairs of clamping flanges are so closely adjacent, as shown at the left in Fig. 1, that the clamping devices would otherwise interfere. By means of an eye 23 provided in its outer end, each clamping device can be seized and withdrawn from operative position, when desired.

In the arrangement shown in Fig. 1, each bipolar electrode has the marginal portion of its supporting plate 10 clamped between inwardly projecting flanges 13 of a pair of the annular frame members, as already pointed out; said plate being insulated by sheet packing and insulation 24 from said flanges and being secured firmly in position by means of a plurality of bolts 25 extending through the plate margin and the flanges, and insulated from said plate by a washer 26. The outer portion of the joint between the flanges 13 may be filled with any suitable luting material 27. It will be noted that this arrangement provides a unitary construction comprising the bipolar electrode with its backing plate, and a pair of annular frame members, said unit being easily assembled with other units of similar character by means of the detachable clamps 20.

Each end wall or end casing member 28 of a multi-cell generator of the type here illustrated, carries but one electrode member 11, and is most desirably provided with an outer wall 29 of good electrical conductivity welded or otherwise maintained in metallic contact therewith. Each of the frame members 14^a at the opposite ends of the apparatus has its inner flange 13^a secured as by welding to an annular plate 30 which projects outwardly about as far as the flanges 15. This projecting portion of the plate 30, in conjunction with the corresponding outwardly extending portion of the plate 29 provides a pair of clamping flanges adapted to be engaged by the clamping devices 20, whereby the end walls of the multi-cell unit are held firmly assembled with the intermediate members of the unit. The plate 30 is best insulated from the plate 28 by a suitable insulating and packing member 31.

A somewhat different arrangement also embodying the principles of the invention is

shown in Figs. 3 and 4, where the cell walls or electrode supporting members and diaphragms are held between cooperating pairs of flanges of double flanged cell frames; but in this case the flanges 32 of the frame members both project outwardly, and the specific form of the clamping devices is different from that above described. In this particular construction, the U-shaped clamping device, instead of being integral, comprises two separate jaw members 33, 34, having a rocking bearing or joint 35 at the outer ends thereof, while an adjusting bolt 36 passing through one of said members and threading into the other member provides means for moving the clamp members toward or from each other. As here shown, the head of the bolt has a spherical bearing at 37 on the member through which said bolt loosely extends. The inner faces of the clamp members are provided with protuberances as indicated at 38 to concentrate the clamping pressure exerted on the interposed frame flanges. In other respects the construction shown in Figs. 3 and 4 is similar in all essentials to that above described.

What I claim is:

1. In electrolytic apparatus, the combination, with cell casing members having a pair of cooperating assembling flanges, of clamp means extending around the adjacent edges of said flanges and holding them together.

2. In electrolytic apparatus, the combination, with a plurality of cell casing members having assembling flanges cooperating in pairs, of a plurality of removable clamps holding the flanges of each pair together.

3. In electrolytic apparatus, the combination, with a plurality of cell casing members having assembling flanges cooperating in pairs, of a plurality of removable clamps holding the flanges of each pair together, and the clamps holding any pair of flanges being in staggered relation to those holding an adjacent pair of flanges.

4. In electrolytic apparatus, the combination, with cell casing members having a pair of cooperating assembling flanges, of U-shaped clamp means extending around the adjacent edges of said flanges and holding them together.

5. In electrolytic apparatus, the combination, with cell casing members having a pair of cooperating assembling flanges, of U-shaped driving clamps extending around the adjacent edges of said flanges and pressing on the non-adjacent faces thereof.

6. In electrolytic apparatus, the combination, with cell casing members having a pair of cooperating assembling flanges, and insulating means interposed between said flanges, of clamp means extending around the adjacent flange edges and holding said flanges together.

7. In electrolytic apparatus, the combina-

tion, with cell casing members having a pair of cooperating assembling flanges, of clamp means extending around the adjacent edges of said flanges and holding them together, and means insulating said clamp means from said flanges.

8. In electrolytic apparatus, the combination, with a plurality of annular cell frames having assembling flanges adapted to co-
10 operate in pairs, end walls, and a plurality of removable clamping devices engaging said flanges and the margins of said end walls to hold the same assembled into a complete cell structure, each said clamping
15 device extending around the adjacent edges of the cooperating flanges of a pair, or around the edges of an end wall and a flange of an adjacent cell frame.

9. In electrolytic apparatus, the combination with cell casing members having assembling flanges cooperating in pairs, of clamp means extending around the adjacent edges of the flanges and holding them together, said clamp means comprising a
20 unitary U-shaped body of resilient metal having approximately parallel inner clamping surfaces, the space between said surfaces narrowing slightly toward the open end of the U, there being an aperture in
25 the clamp means to permit the entry of a tool for removing the clamp.

faces narrowing slightly toward the open end of the U.

10. In electrolytic apparatus, the combination with cell casing members having assembling flanges cooperating in pairs, of clamp means extending around the adjacent edges of the flanges and holding them together, said clamp means comprising a 30 unitary U-shaped body of resilient metal having approximately parallel inner clamping surfaces, the space between said surfaces narrowing slightly toward the open end of the U, there being an aperture in 35 the clamp means to permit the entry of a tool for removing the clamp.

11. In electrolytic apparatus, the combination with cell casing members, each member having a flange thereon, the flanges of 40 adjacent members cooperating one with the other, a clamp member engaging the flanges to hold them together, the engaging portions of the clamping member being capable of movement toward and away from each 45 other.

In testimony whereof I hereunto affix my signature.

WILLIAM G. ALLAN.
